United States Patent Office.

EDWIN R. AUSTIN, OF ELMIRA, NEW YORK.

Letters Patent No. 97,148, dated November 23, 1869.

IMPROVEMENT IN STEP-LADDERS.

The Schedule referred to in these Letters Patent and making part of the same.

Be it known that I, EDWIN R. AUSTIN, of Elmira, in the county of Chemung, and State of New York, have invented a new and improved Clasp, for the purpose of clasping together the main and false legs of Step-Ladders, and other articles adjustable by means of false legs, it being designed to firmly secure them together, and prevent any possibility of slipping.

It is designed as an improvement on the clasp embraced in my claim, in Letters Patent No. 88,831, on Step-Ladder, and issued April 13, 1869, to me. I do hereby declare that the following is a full, clear, and exact description thereof, reference being had to the accompanying drawing, making a part of this specification, and to the letters of reference marked thereon.

To enable others skilled in the art to make and use my invention, I will proceed to describe its construction and operation.

Figure 1. A represents the main leg, J, the false leg.

Figure 2. B, the band, C F, the jaws, and D, the crank.

I make the band B of iron, of sufficient size and strength, and long enough to receive both legs, one end of which is left open to receive the corrugated jaw C, which hangs on pivots, shown at E, and hanging loosely, so that it may take a position at any angle with the band B.

Through the other end of the band passes the shaft

of the crank D, with a corresponding screw-thread cut on the shaft, and in the end of the band.

The shaft is screwed into and through the end of the band, and passes through the jaw F, (being made smaller where it goes through the jaw,) thus forming a shoulder, against which the jaw rests, when pressure is applied by means of the crank D.

The hole through the jaw F is countersunk on the corrugated side, and the end of the shaft is riveted below the surface. The jaw hangs loosely on the shaft, that it may take an angle to the band B, and will be carried to or from the leg by turning the crank.

When it is unscrewed, the false leg J can be moved to any position desired. When screwed up against the leg, it will firmly fasten them together, and the more weight which is placed above them, the tighter will they become, as the jaws cannot slip.

The clasp which this clasp is an improvement on is fully described in the specifications and drawings of step-ladder, at H H, No. 88,831.

What I claim as my invention, and desire to secure by Letters Patent, is—

A clasp, composed of the band B, jaws C and F, crank D, and pivots E, all constructed, arranged, and operating in the manner described, and for the purpose set forth.

Witnesses: EDWIN R. AUSTIN.
